To all whom it may concern:

Be it known that I, MAX SADINOFF, a citizen of the United States, residing at 1766 Union Street, in the Borough of Brooklyn, city of New York, county of Kings and State of New York, have invented a new, original, and ornamental Design for a Curtain or the like, of which the following is a specification, reference being had to the accompanying drawing, forming a part thereof.

The figure is a plan view of a curtain showing my new design.

The broken away portion indicated by the

dotted lines is a continuation of the mesh work, no surface ornamentation being shown thereon. The interrupted shade lines appearing on the drawing represent the background which forms an integral part of the basic curtain.

I claim:

The ornamental design for a curtain or the like as shown and described.

In testimony whereof I have signed this specification.

MAX SADINOFF.
